STARTING DEVICE FOR INTERNAL
COMBUSTION ENGINES

Albert Callsen, Stuttgart, Germany, assignor to
Robert Bosch Aktiengesellschaft, Stuttgart,
Germany

Original application April 18, 1932, Serial No.
606,006. Divided and this application March
26, 1935, Serial No. 13,169. In Germany April
24, 1931

12 Claims. (Cl. 290—38)

The present invention relates to a starting device for internal combustion engines, in which an electric motor is employed and preferably also an inertia mass which is brought to a high speed of rotation by means of the electric motor, and then coupled to the internal combustion engine to be started, and in which a friction clutch is introduced into the driving connection to the pinion engaging in the rim of the flywheel of the engine.

This application is a division of my application Ser. No. 606,006, filed April 18, 1932.

In a known arrangement the pinion is permanently connected with the inertia mass so as to transmit power through a spring-loaded plate-clutch.

This construction has the disadvantage that each time on the engagement of the pinion in the toothed rim of the flywheel of the motor the pinion as well as the toothed rim of the flywheel are strongly worn and even are often damaged. It is also already known in electric starters which have no separate inertia mass to make the plate-clutch inserted between the pinion and the armature of the starting motor capable of transmitting power by a pressure member which can screw axially on the driving shaft. In this case the clutch only establishes the power connection when the pinion on coming into engagement, is prevented from freely rotating. In order however, that the pinion may fully engage, it must become engaged by an auxiliary force before the transmission of the main torque, since an immediate engagement under full load would not be possible because the flank pressure of the teeth is so great from the first moment of the engagement that the axial attractive force of the armature does not suffice to entirely push in the pinion. This second construction is thus not at all possible for flywheel starters because in these the full torque is present immediately upon engagement.

According to the present invention the drawback of the first-mentioned construction is removed, whilst the starting device of the second-named construction is also made applicable to flywheel starters in that the power connection between the pinion and the inertia mass, which is effected by a plate-clutch operated by an axially screwing pressure member, is capable of being initiated at will.

An example of construction of a starter according to the invention is shown in the accompanying drawings, in which:—

55 Figure 1 is a semi-diagrammatic sectional view

of a starter having an axially adjustable armature, in the position of rest,

Figure 2 is a plan of connections of the starting device,

Figure 3 shows the starter in engagement, but with the plate-clutch out of engagement, and

Figure 4 shows the starter in the working position.

In Figures 1, 3 and 4, 1 is the armature of an electric starting motor which in known manner 10 can be axially displaced by the magnetic force of the field winding. On the armature shaft 2 is keyed a flywheel 3 and a pinion 4 is revolubly mounted on the shaft 2. The pinion 4 has a shank 5 which has an external thread 6 of quick 15 pitch. A nut 7 can move on the shank by means of the thread 6. The torque of the armature 1 is transmitted to the pinion 4 through a plate-clutch 8. The plates 9 of the clutch engage by means of projections 10 in recesses 11 in the 20 flange 12 of the flywheel 3, whilst the plates 13 engage by projections 14 in grooves 15 in the nut 7. A spring 17 is tensioned between the nut 7 and a stop 16 on the shank 5 of the pinion, and the spring tends to push the nut 7 against 25 the plates.

In an opening 20 of the casing 18 a lever 19 is pivotally mounted above the plate-clutch 8. One end of the lever projects into the casing, and strikes against a flange 21 on the nut 7 when the 30 lever is rocked, and displaces this latter on the shank 5. The lever is pulled back by a spring 24 into its position of rest. Further, a switch 22 is so arranged on the casing 18, that the switch arm 25 is brought into the switched on position 35 by a finger 23 on the lever 19 when the lever is rocked. The switch arm carries a contact 26, opposite to which a contact 27 is fastened in an insulated manner on the casing. The switch arm 25 is held in its "on" position by a holding 40 coil 28 and is raised by a spring 29 as soon as the holding coil is deprived of current.

In the diagram of connections, Fig. 2, 30 is a battery, one pole of which is connected to earth and the other pole to a brush 34 of the starting 45 armature 1. To the other brush 35 is connected one end of an auxiliary field winding 31 and one end of the holding coil 28 of the switch 22 as well as one end of the main field winding 33. The two other ends of the windings 28 and 31 50 are connected to one pole of the switch 32, the other pole of which is earthed. The second end of the winding 33 is connected to the insulated contact 27 which lies opposite the contact 26 on the switch arm 25 connected to earth. 55

The mode of operation of the starting device is as follows:—

In order to start the internal combustion engine, the switch 32 is closed, thus closing the circuit through the auxiliary field winding 31. It is plain from Fig. 2 that the holding coil 28 in parallel with the auxiliary field winding is also excited by the closing of the switch 32, but as that coil is unable to close the switch 22 which controls the circuit through the main field winding of the motor, the closing of the switch 32 brings the auxiliary field winding only into operation. The result of this is, first, that the armature 1 is axially displaced in known manner by the magnetic force of the auxiliary field winding 31 and set in slow rotation. At this time the clutch is sufficiently engaged, that is, there is a sufficient frictional clutch connection between the armature 1 and the pinion 4, by way of the pressure of the nut 7 against the clutch plates under the tension of the spring 17 and the engagement between the nut and the shank of the pinion, to cause the pinion to partake of the slow rotation of the armature and to be carried along with it until the pinion engages in the toothed rim 36 of the engine flywheel.

As soon as the pinion is in engagement and is prevented by the rim of the flywheel 36 from further rotation, the nut 7, which is sufficiently engaged with the clutch plates by the pressure of spring 17 to continue in rotation, first screws itself along the shank of the pinion further toward the plates in consequence of the threaded connection between the nut and the shank of the pinion and their relative rotary movement and thereby puts the clutch into operation on the pinion.

The torque of the starting motor is however too small in this first switch position to turn over the engine and the motor stops. The lever 19 is now moved into the position shown in Fig. 3. On rocking the lever, the nut 7 is moved away from the clutch plates towards the stop 16 against the tension of spring 17 and thereby the clutch released. At the same time the switch arm 25 is pressed by the finger 23 against the contact 21. The working current circuit is thus now cut in, since the main field winding is also earthed through the switch 22. The starting motor now runs idly with the inertia mass at a high speed and a series wound motor attains of course a very high speed. In order to re-engage the clutch 8, the lever 19 is moved back into its starting position. The spring 17 again pushes the nut 7 towards the plates and thus initiates the driving connection between the armature 1 and flywheel 3 on the one hand and the pinion 4 on the other hand.

The nut 7 now presses the plates together with a force which corresponds to the torque required on the pinion or, what amounts to the same thing, in accordance with the load imposed on the inertia mass in turning over the engine. The working current circuit of the starting motor 65 remains closed by the holding coil 28 so that the starting motor can further assist the action of the flywheel 3. When the speed of the starter on starting the engine is exceeded by the speed of the engine, the pinion comes out of engagement in known manner.

In the above-described mode of operating the starting device, it is to be noted that the succession of operations are the advancement of the pinion into engagement with the toothed rim of the flywheel by displacement of the armature upon

closure of the switch 32 of the auxiliary winding, then disconnecting the pinion from the inertia mass and setting the latter into full speed rotation by movement of the lever 19 to throw out the clutch and close the switch 22 of the main field winding, and then reconnecting the pinion with the inertia mass, and that damage to the pinion and the toothed rim of the flywheel is avoided by reason of the fact that the pinion is advanced into engaging position while the armature and the connected inertia mass are in slow rotation due to the initial excitation of the auxiliary field winding only.

However the pinion can also be put in engagement by the lever 19 instead of with the aid of the displaceable armature, the nut 7 and the shank of the pinion being so formed that the nut can again screw itself back towards the clutch to a distance corresponding to the displacement for engaging the pinion, in order to make the clutch operative.

This makes it possible to effect the engagement of the pinion with the toothed rim of the engine flywheel after the inertia mass has been set in and while it is still in full speed rotation and without damage to either the pinion or the engine flywheel, for at the moment when the pinion is moved by the lever toward the engaging position of the pinion with the engine flywheel the clutch becomes disengaged and the connection between the pinion and the rapidly rotating inertia mass is thereby broken and remains so as long as the lever is pressed against the nut. After the pinion is thus engaged with the toothed rim of the engine flywheel, the lever 19 is moved back to its neutral position and this movement of the lever, of course, relieves the nut 7 from the pressure of the lever against it, whereupon the spring 17 again pushes the nut towards the clutch plates and thus initiates the driving connection between the rapidly rotating inertia mass and the pinion to turn over the engine through the established engagement of the pinion with the toothed rim of the engine flywheel.

In carrying out the last-described method of starting by the device with the electric motor and circuit arrangements shown in the drawings, the first operation step of setting the inertia mass in full speed rotation before the pinion is engaged with the engine flywheel may be performed by leaving the switch 32 for the auxiliary field winding of the motor open so as to avoid that displacement of the armature which would advance the pinion into engagement with the engine flywheel before the inertia mass has been speeded up, and manually closing the switch 22 for the main field winding as may be required to set the armature and the connected inertia mass into full speed rotation.

A further advantage of the starting device according to the invention consists in that the use of a separate free-wheel device for the idle high speed running of the starting motor is avoided.

I declare that what I claim is:

1. A starting device for internal combustion engines comprising an electric motor, having an armature and a shaft extending there-beyond, an inertia mass secured to the armature of said motor, a pinion freely mounted on the shaft of the armature, said pinion having a shank, a nut mounted to rotate on the shank of said pinion, a plate-clutch between said pinion and said inertia mass controlled by said nut and means to displace said nut relatively to said pinion to operate said clutch at will.

2. A starting device for internal combustion engines comprising an electric motor having a rotor and shaft therefor, an inertia mass secured to the rotor of said motor, a pinion freely mounted on the shaft of the rotor, a sleeve secured to said pinion, an external thread on said sleeve, a nut engaging said external thread, a plate-clutch connecting said pinion and said inertia mass and controlled by said nut, a spring urging said nut to engage said plate-clutch, and a lever operable at will to displace said nut to disengage said clutch.

3. A starting device for internal combustion engines comprising an electric motor having a rotor and a shaft therefor extending beyond said rotor, an inertia mass secured to the rotor of said motor, a pinion freely mounted on the shaft of the rotor, a sleeve secured to said pinion, an external thread on said sleeve, a nut engaging said external thread, a plate-clutch connecting said pinion and said inertia mass and controlled by said nut, a spring urging said nut to engage said plate-clutch, a lever operable at will to displace said nut to disengage said clutch and means 25 to close the power circuit of said motor upon operation of said lever.

4. A starting device for internal combustion engines comprising an electric motor having a rotor and a shaft therefor extending beyond said rotor, a power circuit for said motor, an inertia mass secured to the rotor of said motor, a pinion freely mounted on the shaft of the rotor, a sleeve secured to said pinion, an external thread on said sleeve, a nut engaging said external thread, a plate-clutch connecting said pinion and said inertia mass and controlled by said nut, a spring urging said nut to engage said plate-clutch, a lever operable at will to displace said nut to disengage said clutch, a switch to close the power circuit of said motor upon operation of said lever and means to hold the said switch in the closed position.

5. A starter for internal combustion engines comprising an electric motor having an axially displaceable rotor and shaft, a main power circuit, an auxiliary field circuit adapted to axially displace the rotor of said motor and connected in parallel with the main power circuit, a switch in the main power circuit, a holding coil for said switch, an inertia mass secured to the rotor of said motor, a pinion freely mounted on the shaft of said rotor, a nut mounted on said pinion, a plate-clutch operated by said nut and connecting said pinion with said inertia mass, and a lever operable at will to disengage said clutch and to close said switch upon operation.

6. A starting device for an internal combustion engine comprising the combination, with an internal combustion engine having a gear adapted to be driven to turn over said engine, of an electric motor having an axially movable armature, a shaft axially movable with said armature, an auxiliary field winding adapted upon excitation to impart axial movement to said armature and to rotate the same at relatively low speed, a pinion rotatably mounted on said shaft out of engagement with said engine gear in one position of said armature and shaft but movable upon said axial movement of said armature and shaft to engagement with said engine gear, a main field winding for said motor adapted on excitation to impart high speed rotation to said armature, an inertia mass mounted for rotation with said armature, a clutch-controlled driving connection between said inertia member and said pinion, a

power circuit for said motor including said main field winding, a switch to make and break said circuit, and means comprising a lever operable at will in one direction of movement to simultaneously disengage said clutch and close said switch and in an opposite direction of movement to re-engage said clutch.

7. A starting device for internal combustion engines comprising an inertia mass, an electric motor for setting said mass in high speed rotation, a displaceable rotary driving member out of engagement with the engine in the non-starting position, means to shift said driving member into said engagement to start the engine, a friction plate clutch between said driving member and said inertia mass, means comprising a control member automatically movable in dependency on the position of said driving member to control said clutch and manually operable means to displace said control member to operate said clutch at will.

8. A starting device for an internal combustion engine comprising an electric motor, a displaceable driving member out of engagement with the engine in the non-starting position and bodily movable into said engagement to start the engine, means for driving said member from said motor including a multiple-part clutch automatically operating to establish a connection between said driving member and said motor and disengageable to break said connection, a single manually operable member and means actuated thereby to shift said driving member from its said non-starting position into engagement with the engine, to temporarily disengage said clutch upon said engagement of said driving member with the engine and to set said motor into full speed operation while said clutch is thus disengaged.

9. A starting device for an internal combustion engine comprising an electric motor, a displaceable pinion out of engagement with the engine in the non-starting position and bodily movable into said engagement to start the engine, means for driving said pinion from said motor including a multiple-part clutch automatically operating to establish a driving connection between said pinion and said motor and disengageable to break said connection, and means comprising a member manually operable at will in a single stroke in one direction to effect movement of said pinion from its said non-starting position into engagement with the engine, disengagement of said clutch and the setting of said motor into full speed operation.

10. A starting device for an internal combustion engine comprising an electric motor, a rotatable member adapted to be rotatably driven by said motor, said rotatable member being normally out of engagement but movable axially into engagement with a part of the engine to turn over the latter, a clutch normally establishing a driving connection between said rotatable member and said motor and operable at will to break and remake the connection, means to energize said motor for low speed operation thereof and to energize said motor for high speed operation thereof, means automatically operating to move said member axially into engagement with said engine part when said member is connected through said clutch with said motor and the latter is set into low speed rotation; and means operable upon said clutch at will when said member is connected to said engine part to break the connection between said member and said motor while retaining said member in connec-

- tion with said engine part whereby said motor may be set into high speed rotation while said member is disconnected therefrom but connected to said engine part and to restore said connection between said member and said motor whereby the torque of the high speed drive of said motor may be transmitted through said member to said engine part to turn over the latter.
11. A starting device for an internal combustion engine comprising an electric motor operable at low and high speeds, a displaceable pinion out of engagement with the engine in the non-starting position and bodily movable into said engagement to start the engine, means for driving said pinion from said motor comprising a multiple-part friction clutch automatically operating to establish a driving connection between said pinion and said motor and disengageable to break said connection, means including said motor and said pinion-driving means automatically operating to advance said pinion into engagement with the engine upon actuation of said motor at low speed, a member manually operable to temporarily disengage said clutch after said advancement of said pinion into engagement with the engine, and means operated by said member in disengaging said clutch to establish an energizing circuit for the full speed operation of said motor.
12. A starting device for an internal combus-

tion engine comprising the combination, with an internal combustion engine having a gear adapted to be driven to turn over said engine, of an electric motor operable at low and high speeds and having an axially movable armature, means for energizing said motor for low speed rotation and axial movement of said armature during said low speed rotation, a rotatable pinion out of engagement with said engine gear when said armature is in its initial position but shiftable axially into engagement with said engine gear upon said axial movement of said armature, a clutch-controlled driving connection between said motor and said pinion automatically operating upon said low speed rotation and axial movement of said armature to rotate said pinion idly at the low rotation speed of said motor and advance said pinion into engagement with said engine gear and thereafter upon high speed rotation of said motor to impart the torque of said high speed rotation through said pinion to said engine to turn over the latter, and means comprising a lever operable at will, upon said advancement of said pinion into engagement with said engine gear, in one direction of movement to disengage said clutch and energize said motor into high speed rotation and in an opposite direction of movement to re-engage said clutch.

ALBERT CALLSEN. 30
